G. Howe,

Piano Action,

No 9282.

Patented Sep. 28, 1852.

UNITED STATES PATENT OFFICE.

GEORGE HOWE, OF BOSTON, MASSACHUSETTS.

PIANOFORTE-ACTION.

Specification of Letters Patent No. 9,282, dated September 28, 1852.

To all whom it may concern:

Be it known that I, GEORGE HOWE, of Boston, in the county of Suffolk and State of Massachusetts, have invented certain new and useful Improvements in Pianoforte-Actions, and that the following description, taken in connection with the accompanying drawings, hereinafter referred to, forms a full and exact specification of the same, 10 wherein I have set forth the nature and principles of my said improvements by which my invention may be distinguished from others of a similar class, together with such parts as I claim and desire to have 15 secured to me by Letters Patent.

The accompanying drawing which is a side elevation of the action, represents my improvements.

A serious objection has hitherto been experienced in pianoforte actions arising from the noise or "slapping" of the fly of the jack, when it rebounded against its stem after having lifted the hammer. This effect was partly produced by the cloth or packing against which the fly of the jack struck, becoming hardened, as the long distance which the fly had to travel caused it to rebound with great force against the cloth. By my improvements this objection is obviated, the fly being so jointed as to rebound but a very little distance and consequently with very little noise.

a a in the drawing represents the key lever turning on a fulcrum at *b* and having 35 on one end the back catch *c*.

d d is the fly of the jack turning on a fulcrum at *e* in the right angular projection *f* of the stem *f'*. When the key lever is depressed it will be seen that the fly *d d* of the jack will strike against the lever *g g* 40 and raise the hammer *h* in the same manner as in ordinary pianofortes. The end of the jack strikes, when it is retracted by the spring *i* against the regulating button *k*. It will be observed that the fly *d d* of the 45 jack is pointed at *e*, so as to constitute a lever, the short arm of which when it rebounds, strikes against the regulating button *k*. By thus jointing the fly or lever *d d* so close to the regulating button, the short 50 arm of the fly will have but very little distance to travel and consequently rebound without any noise or "slapping" against the cloth of the regulating button.

Having thus described my improvements 55 in pianoforte actions, I state my claim as follows:

What I claim as my invention and desire to have secured to me by Letters Patent is, 60 Jointing the fly of the jack to the stem of the same, so as to constitute a lever, the short arm of which has to move but little distance before it strikes against the regulating button, for the purpose of preventing any noise or "slapping" as above set 65 forth.

GEO. HOWE.
